UNITED STATES PATENT OFFICE.

NIS PETER LAURITZEN, OF SANDUSKY, OHIO, ASSIGNOR TO THE AMERICAN WRINGER COMPANY, OF WOONSOCKET, RHODE ISLAND, A CORPORATION OF RHODE ISLAND.

CLOTHES-WRINGER.

1,229,626.

specification of Letters Patent. Patented June 12, 1917.

Application filed February 21, 1916, Serial No. 79,519. Renewed November 18, 1916. Serial No. 132,233.

To all whom it may concern:

Be it known that I, NIS PETER LAURITZEN, a citizen of the United States, residing at Sandusky, in the county of Erie and State 5 of Ohio, have invented certain new and useful Improvements in Clothes-Wringers, of which the following is a specification.

This invention relates to improvements in clothes wringers and one of the objects 10 of the same is to provide an improved wringer having means for automatically effecting an instant release of the pressure between the rollers in the event that the hand of the operator becomes accidentally 15 caught or the laundry work becomes wedged between the rollers.

To the attainment of these ends, and the accomplishment of other new and useful objects as will appear, the invention 20 consists in the features of novelty in substantially the construction, combination, and arrangement of the several parts hereinafter more fully described and claimed and shown in the accompanying drawings illustrating the invention, and in which,

Figure 1 is a front elevation of a wringer constructed in accordance with the principles of this invention and having a part thereof broken away.

Fig. 2 is an end elevation of the parts shown in Fig. 1.

Referring more particularly to the drawing, the numeral 10 designates the uprights of a wringer frame having arranged 35 in the upper extremities thereof, recesses 11 in which recesses the ends of a cross member 12 are removably seated. The upper roller 13 of the wringer is provided with the usual bearings and projecting from 40 these bearings are shoulders 14 which move within openings in the uprights 10. A cross bar 15 is provided and from the extremities of which arms 16 extend into the openings in the uprights and arranged be- 45 tween these arms 16 and the shoulders 14 are springs 17. Screws 18 passing through the member 12 engage the arms 16 to create a tension on the springs 17 and thereby hold the upper roller 13 yieldingly in oper- 50 ation with the lower roller.

The extremities 19 of the axle of the roller 13 project beyond the outer face of the uprights 10 and pivotally mounted intermediate their ends as at 20, adjacent the

outer face of each of the uprights are ele- 55 ments 21, the lower extremity of each of which terminates adjacent the axle 19 and are each provided with an inclined slot 22 into which the axle extremities project. The upper portion of the element 21 preferably ex- 60 tends beyond the upper ends of the wringer frame and each terminates in a handle 23. The elements are each provided with a slot 24, adapted to receive a lug or extension 25 connected with the extremity of the cross member 12. This portion 24 of the slot is preferably horizontal and terminates in an upright extended portion 26 communicating with the portion 24 so as to form a shoulder 27. The elements 21 thus con- 65 structed and mounted constitute pivoted hooks mounted upon the side bars of the frame and coöperate with the cross mem- 70 ber 12 for holding the latter in predeter- 75 mined position with respect to the frame, 75 and the hooks are provided with goose necks at their upper ends adapted to re- 80 ceive extensions 25 when released by the hooks for limiting the upward movement of the element 12. The hooks have tail por- 85 tions arranged in the path of travel of one of the pressure rolls on the separation of the rolls for moving the hooks out of en- 90 gagement with the extensions 25 for re- 95 leasing the cross member 12. When the 95 cross member 12 is seated in the recesses 11 and the tension is exerted upon the springs 17, the projections 25 on the cross member 12 will be seated in the slots 24 and the upper adjustable roller 13 will be main- 100 tained under a tension. During the oper- 100 ation of the device when the laundry work is passed through the rolls, and the rolls operated, the separating movement of the roll 13 from the lower roll will cause the 105 axles 19 to rise in the slots 22 and en- 105 gaging the inclined faces of the slot will cause the elements 21 to rock about their pivots 20, during the rising and falling movement of the upper roll.

Under normal conditions the swinging movement of the element 21 will be such that the lugs or projections 25 will not pass beyond the shoulders 27 in the slots, but in case of an emergency, such for in- 110 stance as the hand of the operator being caught between the rolls, or the laundry being wedged between the rolls, the upper

roll will rise to a greater extent and in so doing the lugs 25 will pass beyond the shoulder 27, so that the upright portion 26 of the slot will be in a position over the lugs 25 so that the tension of the springs 17 will cause the cross member 12 to rise and the lugs or projections 25 will ride into the slots 26, and thereby release the tension of the upper roll 13.

10 When it is desired to re-set the device, all that is necessary is to press the cross member 12 down into the recesses 11 and swing the elements 21 about their pivots into the position shown in full lines in Fig. 2.

15 With this improved construction it will be manifest that the device is entirely automatic in operation and that under normal conditions the roll 13 will rise and fall to a predetermined extent but in the case of emergency, the action of the roll 13 upon the element 21 will automatically shift the latter so that the tension on the springs will be automatically released.

25 What is claimed as new is:

1. A clothes wringer embodying a fixed roll, a coöperating roll movable toward and away from the fixed roll, means for maintaining a tension upon the movable roll and means operated by said movable roll for releasing the said tension means when said movable roll is moved to an abnormal position.

2. A clothes wringer embodying a fixed roll, a coöperating roll movable toward and away from the fixed roll, means for maintaining a tension upon the movable roll and means operatively connected with the said movable roll for automatically releasing the said tension means.

3. A clothes wringer embodying a fixed roll, a coöperating roll movable toward and away from the fixed roll, means for maintaining a tension upon the said movable roll, and means with which one of the rolls has connection and operating automatically at a predetermined point in the separating movement of the rolls for releasing the said tension.

4. A clothes wringer embodying a tension controlled roll and a coöperating roll, said rolls being separable, locking means for maintaining the tension, and means whereby the said locking means will be automatically released at a predetermined point in the separation of the rolls, said locking means embodying a shiftable element operatively related to one of the rolls.

5. A clothes wringer embodying a tension controlled roll, springs confined against the ends thereof, a pressure member, a shiftable element mounted upon the wringer frame and operating to lock the pressure member to maintain the springs under tension, and means for automatically shifting said ele-

ment to unlock said member to release the tension of the springs upon the roll upon the separation of the rolls.

6. A clothes wringer embodying a tension controlled roll, springs confined against the ends thereof, a pressure member, a shiftable element mounted upon the wringer frame and operating to lock the pressure member to maintain the springs under tension, and means for automatically shifting said element to unlock said member to release the tension of the springs upon the roll, the said element and roll being provided one with an inclined face and the other with a projection, one movable over the other for shifting said element.

7. A clothes wringer embodying a tension controlled roll, springs confined against the ends thereof, a pressure member, and a locking element for the said pressure member for maintaining the springs under tension, said element adapted to be automatically shifted by the shifting movement of said roll, to release the tension of said springs on the roll, said locking element being provided with means whereby the roll may be shifted to a predetermined extent without releasing the tension of the said springs.

8. A clothes wringer embodying a tension controlled roll, springs confined against the ends thereof, a pressure member, and a locking element adjacent each end of the roll for maintaining the springs under tension and coöperating with the respective ends of the pressure member, said elements automatically shiftable by the shifting movement of said roll, to simultaneously release the tension of the springs on both ends of the roll, and provisions whereby the roll may be shifted to a predetermined extent without releasing the tension of said springs, the said provisions embodying slotted connections between the ends of the rolls and the said element.

9. A clothes wringer, comprising a frame having pressure rolls and pressure means for said rolls, a top bar having means for adjusting said pressure means, movable members carried by the side bars of said frame co-acting with said top bar for holding said top bar in predetermined position within said frame, and means actuated by the vertical movement of one of said pressure rolls, for moving said movable members out of path of travel of said top bar.

10. A clothes wringer comprising a frame having pressure rolls and pressure means for said rolls, means for normally holding said pressure means in predetermined position, and means actuated by the separation of said pressure rolls for releasing said means.

11. A clothes wringer, comprising a frame having pressure rolls and pressure means for said rolls mounted therein, a movably

mounted member mounted in said frame carrying means for adjusting said pressure means, means for normally holding said movably mounted member in predetermined position, and means actuated by the separation of said pressure rolls for releasing said retaining means.

12. A clothes wringer having pressure rolls and pressure means for said rolls including a movably mounted member carrying means for adjusting said pressure means, movable latches for holding said movable member in predetermined position within said frame, and means actuated by the separation of said rolls for moving said movable latches out of the path of travel of said movably mounted member for releasing said pressure means.

13. A clothes wringer comprising a frame having pressure rolls and pressure means for said rolls mounted therein, a movable member mounted in said frame carrying pressure screws for adjusting said pressure means, means for holding said movable member in predetermined position therein, and means actuated by the separation of said rolls for releasing said retaining means.

14. A clothes wringer, comprising a frame having pressure rolls and pressure means for said rolls mounted therein, a top bar movably mounted in said frame having pressure screws for adjusting said pressure means, said top bar having projections at its ends, pivoted hooks mounted on the side bars of said frame coöperating with said projections for holding said top bar in predetermined position within said frame, said hooks having goose necks at their upper ends adapted to receive said projections when released by said hooks for limiting the upward movement of said top bar, said hooks having tail portions arranged in the path of travel of one of the pressure roll shafts on the separation of said rolls for moving said hooks out of engagement with said projections for releasing said top bar.

15. A clothes wringer, comprising a frame having pressure rolls and pressure means for said rolls mounted therein, a top bar movably mounted in said frame having

means for adjusting said pressure means, pivoted hooks for holding said top bar in predetermined position within said frame, said hooks having means for limiting the upward movement of said top bar within said frame, and tail portions formed on said hooks arranged in the path of travel of one of said pressure rolls on the separation of said rolls for releasing said top bar.

16. A clothes wringer, comprising a frame having pressure rolls and pressure means for said rolls mounted therein, a top bar movably mounted in said frame having pressure screws for adjusting said pressure means, pivoted hooks actuated by the separation of said pressure rolls, said hooks having means for holding said top bar in predetermined position within said frame and for limiting the upward movement thereof.

17. A clothes wringer comprising a frame having pressure rolls and pressure means for said rolls mounted therein, a top bar movably mounted in said frame having means for adjusting said pressure means, pivoted hooks for holding said top bar in predetermined position within said frame, said hooks having means for limiting the upward movement of said top bar.

18. A clothes wringer, comprising a frame having pressure rolls and pressure means for said rolls mounted therein, a top bar movably mounted in said frame having means for adjusting said pressure means, movable members for holding said top bar in predetermined position within said frame, said movable member having means for limiting the upward movement of said top bar, said movable members being actuated by the separation of said pressure rolls for releasing said pressure means.

In testimony whereof I have signed my name to this specification, in the presence of the subscribing witnesses, on this 18th day of February A. D. 1916.

NIS PETER LAURITZEN.
